FIRE ESCAPE DEVICE

Arthur R. Burke, Rochester, Minn., assignor of forty-nine four-hundredths to Cecil E. Genthaler, forty-nine four-hundredths to Charles F. Shields, forty-nine four-hundredths to Elmer Lee, and forty-nine four-hundredths to John Ryan, all of Rochester, Minn.

Application May 15, 1935, Serial No. 21,560

4 Claims. (Cl. 227—39)

My invention relates to fire escape devices and particularly to devices providing for descent of persons from a window of a building to the ground.

5 An object of my invention is to provide simple, inexpensive, effective and easily used fire escape device of the class described.

Another object is to provide such a device which may normally be kept in compact condition to facilitate storage and transportation and yet may 10 be quickly and easily placed in operative condition.

Still another object is to provide such a device including a flexible trough-like structure adapted 15 to be attached at its upper end to either the frame or sill of the window of a building and to be held at its lower end by a person standing on the ground outside of said building.

These and other objects and advantages of the 20 invention will be more fully set forth in the following description made in connection with the accompanying drawing, in which like reference characters refer to similar parts throughout the several views and in which:—

25 Fig. 1 is a view of my fire escape device compactly rolled up as for storage or transportation;

Fig. 2 is a view of my device as seen from the inside of a window frame with which it is associated in operative condition;

30 Fig. 3 is a sectional view taken along the line 3—3 of Fig. 2 as indicated by the arrows;

Fig. 4 is a sectional view taken along the line 4—4 of Fig. 1 as indicated by the arrows, and

35 Fig. 5 is a longitudinal sectional view of my device attached to a ledge.

Referring to the drawing, my fire escape device includes a trough-like chute C formed of flexible sheet material such as canvas or other suitable sheet material and comprising a floor portion 6 40 and a pair of side wall or railing portions 7 extending upwardly from respective edges of the floor portion at substantially right angles thereto.

The upper edges of the side wall portions 7 of the chute C are reinforced by hemming them 45 over ropes 8 as shown best in Fig. 3 and stitching the ropes 8 to the hemmed portions of the side walls 7. At the lower end of the chute C the respective ropes 8 extend outwardly of the end of the hem and are bent back and stitched into the 50 hem, as shown, to form anchoring loops 8a. Other relatively short pieces of rope are stitched to the upper edge of each side wall portion 7 at intervals to provide a series of spaced anchoring loops along the length of each side wall portion 7 as shown.

The chute C of my device is adapted to extend outwardly and downwardly from a window or other opening in the wall of a building to the ground adjacent the wall and hence suitable means is provided at the upper end of the chute C for connecting the same to the building wall for support thereby.

An elongated supporting member is provided, such as the rod 10 having a length somewhat greater than the width of the wall opening with 10 which my device is to be associated. The upper end of the floor portion 6 of the chute C is formed into a hem 6a through which the rod 10 extends. The outer portions of the rod 10 may be placed in engagement with portions of a building wall 15 closely adjoining respectively opposite sides of an opening in the wall with which my device is associated, as illustrated in Fig. 2 wherein my device is shown associated with a window opening O formed in a wall W and provided with a window frame F.

Each end portion of the rod 10 is provided with a generally inverted U-shaped element 11 attached thereto in a certain manner to be described. Each U-shaped element 11 includes one 20 leg disposed closer to the center of the rod 10 than the remaining leg and to be hereinafter referred to as the inner leg and a remaining leg to be hereinafter referred to as the outer leg.

The lower end of the inner leg of each of the 30 U-shaped elements 11 is formed into a loop 11a encircling the rod 10. Each loop 11a has an internal diameter substantially larger than the external diameter of the rod 10 and, with the U-shaped elements 11 positioned as shown in Fig. 35 2, lies in a vertical plane inclining inwardly of the wall W and outwardly of the center of the rod 10 at an angle of approximately 45 degrees as shown in Fig. 2 so that the U-shaped element 11 may be swung about the longitudinal axis of 40 its inner leg between positions wherein the plane of the U-shaped element 11 lies respectively normal to the longitudinal axis of the rod 10 and in position to include the longitudinal axis of the rod 10 as respectively shown in Fig. 5 and Fig. 2. 45

The upper ends of the respective side-wall portions 7 of the chute C are provided with hems through which the inner legs of the respective U-shaped elements 11 extend as shown. The upper ends of the ropes 8 are secured to the upper 50 portions of the inner legs of the respective U-shaped elements 11 whereby the chute C will be supported by the ropes 8 and depend therefrom in the manner of a trough.

The remaining or outer leg of each of the U- 55

shaped elements **11** is flattened and bent inwardly to form a hook-like attachment element **11b** best shown in Fig. 4. Each end of the rod **10** is provided with a notch **10a** within which a portion of the attachment element **11b** is received as shown in Fig. 4. Each outer end of the rod is externally screw-threaded and is provided with a retaining nut **12** for holding the attachment element **11b** in the notch **10a** of the rod **10**.

10 The window frame **F** with which my device is shown in Figs. 2 and 3 is provided with stout screw-hooks **13** on which the upper portions of the respective inverted U-shaped elements **11** may be hung as shown. However, it should be apparent that my device may be associated with a window frame in the manner illustrated without resorting to hooks such as the hooks **13**.

When use of my fire escape device becomes necessary the rod **10** and U-shaped elements **11** thereof may be easily and rapidly placed in operative relation with a window frame **F** and screw-hooks **13** as shown in Figs. 2 and 3 with the chute **C** hanging out of the window. The anchoring loops **8a** or a pair of the anchoring loops **9** may be 25 grasped by a person or persons on the ground outside the wall **W** or may be connected to any suitable object to so anchor the lower portion of the chute **C** that the chute **C** is inclined at an angle 45 degrees or thereabouts with respect to 30 the ground.

If the full length of the chute **C** is required to reach a point adjacent the ground when my device is placed in operative condition as above described the anchoring loops **8a** at the lower end 35 of the chute are used and if less than the full length of the chute is required a suitable pair of anchoring loops **9** are used.

A person desiring to descend to the ground by means of my device may seat himself on the 40 upper end of the floor portion **6** of the chute **C** with his hands grasping the upper marginal parts of the respective side wall portions **7** of the chute. The said person may then slide down the chute **C** or slowly descend in the chute **C** regulating his 45 speed of descent by shifting his grasp with first one hand and then the other to successively lower points on the marginal parts of the side wall portions **7** of the chute **C**.

When my device is not in use it may be compactly rolled as follows. The side-wall portions **7** are folded inwardly against the floor portion **6** of the chute **C** and the floor and side wall portions **6** and **7** are tightly rolled adjacent the rod **10** to 50 assume the positions thereof shown in Figs. 1 and 55 5, after which the roll thus formed may be tightly encircled by a suitable binding element such as the strap **14**. It is of course preferable that my device, rolled as described, normally be kept within a building and close to the wall opening with 55 which it is intended to be used.

If it is desired that the upper end of my device be connected to and supported by a portion of a building, such as the element **15**, the nuts **12** are removed, the U-shaped elements **11** are slid outwardly on the rod **10** to disengage the hook-like attachment elements **11b** from the notches **10a** of the rod **10** and the U-shaped elements **11** are swung into a plane normal to the longitudinal axis of the rod **10**. Then the U-shaped elements 60 become hooks suited for engagement with the element **15** of a building in the manner shown in Fig. 5.

It is apparent that I have invented a novel, simple, inexpensive and effective fire escape device 75 which may normally be stored in efficiently com-

pacted condition and which can be very easily and quickly placed in operative condition.

It will, of course, be understood that various changes may be made in the form, details, proportions and arrangement of the parts, without departing from the scope of my invention, which, generally stated, consists in a device capable of carrying out the objects above set forth, and in the novel parts and combinations of parts disclosed and defined in the appended claims. 10

Attention should perhaps be called to the fact that the elements **11** are slidable longitudinally of the rod **10** within limits so as to permit adjustment to bear against the inner sides of uprights spaced varying distances apart. This adapts the 15 device for use with windows of varying widths. Preferably the fabric material forming the chute **C** is made of fire resistant material.

What is claimed is:—

1. Fire escape apparatus comprising a trough-like structure adapted to extend outwardly and downwardly from a portion of a building and means at the upper end of said structure for engagement with said building, said means including a rigid, elongated horizontal member adapted to bridge between and bear against a pair of uprights of said building, a pair of generally inverted U-shaped elements associated with the respective ends of said rigid member, each of said U-shaped elements being connected to said rigid member to be swingable with respect thereto about the axis of one of its legs between positions wherein the plane of said U-shaped element is respectively parallel to and at right angles to a vertical plane containing the longitudinal axis of said rigid member whereby said U-shaped elements comprise a pair of hooks when at right angles and are adapted to bear against said uprights when parallel to the axis of said rigid member. 20

2. Fire escape apparatus comprising a trough-like structure adapted to extend outwardly and 25

downwardly from a portion of a building and means at the upper end of said structure for engagement with said building, said means including a rigid, elongated horizontal member adapted to bridge between and bear against a pair of uprights of said building, a pair of generally U-shaped elements associated with the respective ends of said rigid member, each of said U-shaped elements having the free end of one leg thereof 30 formed into one eye encircling said rigid member and disposed in a plane obliquely angled with the plane of the U-shaped element whereby each of said U-shaped members may be swung between 35 positions wherein its plane is respectively parallel to and at right angles to the longitudinal axis of said rigid member, said U-shaped elements comprising hooks when disposed at right angles to said rigid member, and a pair of 40 releasable means for connecting the free ends of the remaining legs of the respective U-shaped elements to said rigid member when said U-shaped elements are parallel to said rigid member whereby said U-shaped elements are held in 45 vertically extending relation to said rigid member and are adapted to bear against the respective ones of said uprights. 50

3. Fire escape apparatus comprising a trough-like chute formed of fabric and including a floor 55 and side wall portions extending upwardly from the edges of said floor, flexible elongated tension elements extending longitudinally of and secured to the upper marginal portions of the respective side walls to support said chute, said chute being 60

adapted to extend diagonally outwardly and downwardly from a portion of a building to a point adjacent the ground, and means at the upper end of said chute for engagement with 5 said building, said means including a rigid, elongated horizontal member adapted to bridge between and bear against a pair of uprights of said building, a pair of generally U-shaped elements associated with the respective ends of said 10 rigid member, each of said U-shaped elements having the free end of one leg thereof formed into an eye encircling said rigid member and disposed in a plane obliquely angled with the plane of said U-shaped element whereby each of 15 said U-shaped members may be swung between positions wherein its plane is respectively parallel to and at right angles to the longitudinal axis of said rigid member, said U-shaped elements comprising hooks when disposed at right 20 angles to said rigid member, and a pair of releasable means for connecting the free ends of the remaining legs of the respective U-shaped elements to said rigid member when said U-shaped elements are parallel to said rigid member where-

by said U-shaped elements are held in vertically extending relation to said rigid member and are adapted to bear against the respective ones of said uprights, the upper ends of said tension elements being connected to the upper portions of 5 the first mentioned legs of the respective U-shaped elements.

4. Fire escape apparatus comprising a trough-like structure adapted to extend outwardly and downwardly from a portion of a building, means 10 attached to the upper end of said structure for engagement with said building for at least partial support of said structure therefrom, said means including a rigid horizontally disposed elongated member adapted to be bridged between 15 a pair of uprights of said building so as to bear thereagainst, and elements mounted on the respective end portions of said member forming loops adapted for encircling inwardly projecting elements suitably located on said uprights to restrain 20 said member against downward movement.

ARTHUR R. BURKE.
